UNITED STATES PATENT OFFICE.

HENRY LARDNER AND CHARLES BRENT, OF NILES, MICHIGAN.

FILTER.

SPECIFICATION forming part of Letters Patent No. 595,182, dated December 7, 1897.

Application filed May 7, 1897. Serial No. 635,531. (No model.)

To all whom it may concern:

Be it known that we, HENRY LARDNER and CHARLES BRENT, citizens of the United States, residing at Niles, in the county of Berrien 5 and State of Michigan, have invented a new and useful Filter, of which the following is a specification.

This invention relates to filters, its object being to provide a device of this character 10 which shall be exceedingly simple in construction and efficient in operation and through which the flow of water may be quickly reversed for the purpose of cleansing the filter-bed.

15 The invention also contemplates the use of compressed air, which will be stored during the filtering operation, to aid the water in cleansing the filter-bed.

With these and other objects in view the 20 invention consists in the several details of construction and combination of parts, as will be hereinafter fully described, and particularly pointed out in the claims.

In the drawings, Figure 1 is a vertical section of a filter made in accordance with our 25 invention. Fig. 2 is a horizontal section on the line $x-x$ of Fig. 1. Fig. 3 is a horizontal section on the line $y-y$ of Fig. 1. Fig. 4 is an end view of the pump, showing a part of 30 the suction-pipe and the valved opening therein for the admission of air.

Similar reference-numerals indicate similar parts in the several figures.

1 indicates a casing, preferably cylindrical in form, and the ends 2 of which are convex. 35 3 indicates supporting-legs which are provided with flanges 4 at their upper ends, and these flanges are firmly secured to the lower end of the casing by means of bolts 5. Each 40 end of the casing is provided with a central opening 6.

7 indicates an elbow-pipe, which is provided with a flange 8 to fit over the opening 6 in the upper end of the casing.

45 9 indicates a perforated pipe, which is closed at its lower end and provided at its upper end with a flange 10. This pipe is fitted within the casing, and the flanges 8 and 10 are firmly secured together and to the casing 50 by means of bolts 11.

12 indicates a T-coupling, the vertical arm of which is provided with a flange 13, and this T-coupling is adapted to fit over the opening 6 in the lower end of the casing.

14 indicates a nipple which is provided with a flange 15 at its lower end, and this nipple is arranged on the inside of the casing, and the flanges 13 and 15 are firmly secured together and to the casing by means of the bolts 16. The upper end of the nipple 14 is 60 provided with a cap 17, which may be integral with the nipple or be secured to it in any suitable manner, and from this cap a series of perforated pipes 18 radiate. These pipes extend at their outer ends into close proximity with the vertical wall of the casing, and the perforations in the pipes extend entirely around them.

65 19 indicates sand or other suitable filtering material which occupies about two-thirds of the interior of the casing, and the perforated pipes 18 are embedded in the sand and firmly supported thereby.

20 indicates a two-way valve with which the supply-pipe 21 communicates. The water 75 to be filtered is fed through this pipe 21, which may, if necessary, be connected to a pump 22.

23 indicates a three-way valve, and 24 a pipe which connects the valves 20 and 23.

25 indicates a pipe leading from one side 80 of the valve 23 to the elbow-pipe 7, and 26 is a pipe leading from the opposite side of the valve 23. This pipe 20 serves as a discharge-pipe when the current of water is reversed, in order to cleanse the filter-bed.

85 27 indicates a pipe leading from the valve 20 on the side opposite to that from which the pipe 24 leads, and this pipe 27 is connected to one side of the T-coupling 12. From the other side of the T-coupling 12 a pipe 28 90 leads, and through this pipe the filtered water is conveyed from the casing into the storage-tank or the water-main, as desired. The pipe 28 is provided with a valve 29, by means of which the flow from the filter through the pipe 28 may be cut off when necessary. Each 95 of the valves 20 and 23 is provided with a lever or handle 30, and these levers are connected by means of a rod 31 in order that the valves may be simultaneously operated.

32 indicates an air-pipe leading from the elbow 7, and 33 is a three-way valve fitted in the pipe 32. From the valve 33 a branch pipe 34 leads to a tank 35, into which air is forced during the process of filtering and caused to accumulate therein under pressure. This air may be drawn in through a valved opening 41 in the suction-pipe 42 in close proximity to the pump-chamber, (see Fig. 4,) or it may be supplied by an independent pump.

36 indicates a head which is hollow and from which a series of perforated pipes 37 radiate. A pipe 38 leads from the upper end of the compressed-air tank 35 into the lower end of the head 36, and this pipe is provided with a valve 39, by means of which the flow of air from the tank to the head can be controlled.

20 The upper end of the casing is provided with a manhole, which is closed by a cap or cover 40, which may be secured in position in any well-known and approved manner.

In operation the plugs in the valves 20 and 25 will be set so that the water will flow from the pipe 21 up through the pipe 24, through the valve 23, pipe 25, and into the casing through the perforated pipe 9, and it will then pass down through the filtering material 30 and be discharged through the perforated pipes 18 into the pipe 28, by which it will be conveyed to any desired place. When it is desired to cleanse the filter-bed, the valve 29 will be closed and the plugs of the valves 20 35, and 23 be turned so that the water will flow from the pipe 21 through the pipe 27 and up through the nipple 14, through the pipes 18, and be forced up through the filtering material. At the same time the valve 39 will be 40 opened to permit the compressed air to flow from the tank out through the perforated pipe 37, which, as shown, are embedded in the sand or other filtering material a short distance below its upper surface, and the force of the 45 water and the compressed air will thoroughly agitate the material of which the filter-bed is formed and wash out all the mud and other impurities which may have accumulated therein, and the mud and other impurities 50 will be carried off by the water which will be forced through the perforated pipe 9, thence through the pipe 25, valve 23, and discharge-pipe 26. The filtering material will not, however, escape with the mud and other impurities for the reason that it is too heavy to be 55 lifted any great distance upwardly and for the further reason that it will not be able to pass through the perforations in the pipe 9.

From the foregoing description it will be seen that our device is exceedingly simple and contains but few parts; also, that the reversal of the current through the filter-bed can be quickly accomplished by the mere shifting of the plugs in the valves 20 and 23, 60 which plugs are so connected as to be oper-

ated simultaneously. It will also be seen that the air, which has been stored in the tank 35 during the filtering operation, will greatly aid the water in cleansing the filter-bed.

It will be understood that changes in the form, proportion, and minor details of construction may be resorted to without departing from the spirit or sacrificing any of the advantages of this invention.

Having thus described the invention, what we claim is—

1. In a filter, the combination with the casing, the filtering material contained therein, a water-supply pipe, a perforated pipe connected to the supply-pipe and extending into the casing at its upper end above the filtering material, a branch pipe having a valve connection to the supply-pipe, a series of radiating perforated pipes seated in the filtering material near the bottom of the casing, a discharge-pipe for the filtered water with which the series of radiating perforated pipes communicate, a pipe leading from the discharge-pipe and having a valve connection with the supply-pipe, and means to operate the valves to reverse the normal flow of water and cause it to enter the filter through the discharge-pipe, and pass therefrom with impurities from the filtering material through the perforated pipe, the supply-pipe and the branch pipe connected to the supply-pipe, substantially as described.

2. In a filter, the combination with the casing, and the filtering material contained therein, of a storage-tank for compressed air, a series of radiating perforated pipes seated in the filtering material near its upper surface, a hollow head from which said pipes radiate, and a valved pipe connection between the air-tank and the hollow head, whereby the compressed air may be discharged into the filtering material to agitate it, substantially as described.

3. In a filtering apparatus, the combination with the casing, the filtering material contained therein, and the supply-pipe through which the water is conveyed to the filter, of a pump connected to the supply-pipe, a valved opening in the suction-pipe in close proximity to the pump-chamber for the admission of air, a compressed-air reservoir, a valved pipe leading from the water-supply pipe to the said reservoir, a series of radiating perforated pipes seated in the filtering material near its upper surface, a hollow head from which said pipes radiate, and a valved pipe connecting the air-reservoir and the hollow head, substantially as described.

4. In a filter, the combination of the casing, the filtering material contained therein, inlet and outlet pipes at the opposite ends of said casing, a supply-pipe, pipe connections between the supply-pipe and said inlet and outlet pipes, a discharge-pipe connected to the inlet-pipe at the upper end of the casing and

through which the impurities in the filtering material are discharged when the latter is cleansed, controlling-valves interposed in the pipe connection between the supply-pipe and said inlet, outlet and discharge pipes, levers on the valve-plugs, and a rod connecting said levers, substantially as described.

In testimony that we claim the foregoing as

our own we have hereto affixed our signatures in the presence of two witnesses.

HENRY LARDNER.
CHARLES BRENT.
